UNITED STATES PATENT OFFICE.

EDWIN J. JOHNSON, OF MONTREAL, QUEBEC, CANADA, ASSIGNOR TO DOMINION CARTRIDGE COMPANY, LIMITED, OF MONTREAL, CANADA.

MUSHROOMING BULLET AND METHOD OF MAKING SAME.

Application filed February 28, 1925. Serial No. 12,329.

This invention relates to new and useful improvements in bullets, and a method of making same, and the object of the invention is to provide a sporting bullet of the expansive or mushrooming type which will be inexpensive to manufacture and which will flatten out at the nose without breaking off forming a ragged or broken end when it hits an animal target, a feature which is very common in bullets now in use. In other words, the outer shell of my bullet remains intact after it has mushroomed to its final shape.

Another object of this invention is to provide a bullet of the class stated, which will be safely handled and which can, without fear of accident due to premature explosion, be used in repeating rifles having magazines.

A further object is to provide an expansive bullet which will give the same accuracy as a solid nose bullet, such as military bullets or bullets used for high class target practice.

In my invention, I provide an easily manufactured bullet of the class stated, provided with an outer shell of copper or the like and an inner core of lead or like soft metal, said core being provided with a recess or cavity at one end adapted to be closed by the nose of the shell. In manufacturing the shell, it is drawn from a solid piece of copper, leaving one end open, and into the open end is placed the core, after which the edges of the open end of the shell are turned inwardly to hold the core in position. To ensure that the fore part of the core is engaging with the inner walls of the shell at the nose, an indent is pressed therein, this indent also providing a feature which prevents an adjacent cartridge from being prematurely exploded when the bullet is used in a rifle having a magazine.

40 In the drawings;—

Fig. 1 is a full size sectional elevation of my improved expansive bullet.

Fig. 2 is an enlarged sectional elevation of the shell or casing before the core is placed therein.

Fig. 3 is an enlarged sectional elevation of the core.

Fig. 4 is an enlarged sectional elevation of the assembled bullet.

50 Fig. 5 is a plan looking on the nose of the assembled bullet.

Fig. 6 is a sectional plan of the bullet taken on the line 6—6, Figure 4.

Fig. 7 is an enlarged sectional elevation of the bullet as it appears when mushroomed or flattened out.

Fig. 8 is a diagrammatic illustration of the steps through which the shell passes in the course of manufacture, that is, from the solid block of material until it has assumed the shape shown in Figure 2.

Referring more particularly to the drawings, 11 designates a solid piece of copper which is pressed into its final shape, designated 12, after passing through the stages 13, 14 and 15. This is accomplished by the well known process of passing the material through a series of punches and dies (not shown). I have shown the material passing through four stages but this may be increased or decreased according to the equipment of the plant manufacturing same. The shell is shown enlarged in Figure 2. It will be noticed that the shell is slightly tapered from its base 16, which is the open end of the shell, until it approaches a point approximately midway between the base and the nose 17. From this point it is tapered more abruptly towards the nose by curving the casing towards its centre. This provides a one-part shell, into which is placed a lead slug 18 or core of soft material, said core being adapted to conform to the shape of the inner wall of the shell and is provided with a recess or cavity 19, the depth of which is approximately equal to half the length of the core. The core is pushed or pressed into the shell from its open base and the closed end or nose of the case is adapted to seal the open end of the cavity and confine a predetermined volume of air therein. The edge 20 of the base of the shell is turned inwardly to engage with and sink into the base 21 of the core to hold same in position. A cannelure 22 may be formed in the outer wall of the shell for receiving the upper edge of the cartridge (not shown). An indent 23 is pressed in the shell at its nose, so that there is no pointed or rounded nose on the bullet which might contact with and pierce the primer of an adjacent cartridge when the bullet is used in a magazine rifle. This also serves to identify this type of bullet from the regular hard pointed bullets. The pressing of the indent also ensures that the upper edge of the core 105 will contact with the shell and support same

at its nose. Modifications may be made in the shape of the bullet without departing from the spirit of the invention.

When the bullet strikes the flesh of the animal or object at which it has been aimed, the nose of the bullet mushrooms or flattens out, as shown in Figure 7. This is caused by the hollow or weakened construction of the nose of the soft metal or lead core which allows this to spread. The shell, being made of tougher and harder material, remains intact and holds the ends of the cavity closed, thereby preventing the bullet from bursting and breaking up within the wound or hole where the bullet is lodged. It will be seen that the base of the core has moved towards the nose of the shell and that the cavity is closed by the lead, which tends to move toward said nose when the bullet has hit its mark. As will be seen from the foregoing, the bullet is simply and economically manufactured and is supported by its core from the base to the nose of the bullet, thereby providing a bullet which can be easily handled

without damaging same. By providing the indent at the nose, the danger of exploding adjacent cartridges in repeating or magazine rifles is eliminated. The bullet, being provided with a one-piece shell, is very accurate and can be used with the same confidence as a solid or military bullet used in high class target practice.

Having thus described my invention, what I claim is:

A mushroom bullet comprising a one piece outer hollow metal shell closed at the nose end and open at the other end, a core of softer metal secured in and filling said shell, said core being formed with a cavity extending inwardly from the nose end of the core and affording an air pocket and said shell having the nose end thereof depressed into the mouth of said pocket to seal said mouth and to form an outwardly facing depression at the nose end of the shell.

In witness whereof, I have hereunto set my hand.

EDWIN J. JOHNSON.
